[57] CLAIM

The ornamental design for a combined bottle and cap, substantially as shown and described.

DESCRIPTION

FIG. 1 is an elevational view of one face of a combined bottle and cap showing my new design, the other two faces being the same in appearance;

FIG. 2 is an elevational view of the edge between two faces, the other two edges being the same;

FIG. 3 is an elevational view looking from the left of FIG. 1;

FIG. 4 is a top plan view;

FIG. 5 is a bottom plan view;

FIG. 6 is a sectional view taken on the line 6—6 of FIG. 1;

FIG. 7 is a front elevational view of one face of the cap, the other two faces being the same in appearance;

FIG. 8 is an elevational view of the edge between two faces, the other two edges being the same;

FIG. 9 is an elevational view looking from the left of FIG. 7;

FIG. 10 is a top plan view;

FIG. 11 is a bottom plan view;

FIG. 12 is a sectional view taken on the line 12—12 of FIG. 7.
